CLAIM

The ornamental design for a roofing shingle, as shown and described.

DESCRIPTION

FIG. 1 is a top perspective view of a roofing shingle according to the present invention.

FIG. 2 is a top plan view of the roofing shingle shown in FIG. 1.

FIG. 3 is a left side view of the roofing shingle shown in FIG. 1.

FIG. 4 is a right side view of the roofing shingle shown in FIG. 1.

FIG. 5 is a bottom view of the roofing shingle shown in FIG. 1.

FIG. 6 is a rear view of the roofing shingle shown in FIG. 1; and,

FIG. 7 is a front view of the roofing shingle shown in FIG. 1. The broken lines shown herein are for illustration of environmental structure and form no part of the claimed design.
